(57) **CLAIM**

The ornamental design for a ring toss game, as shown and described.

DESCRIPTION

FIG. 1 is a front elevation view of a ring toss game showing my new design, with the rear elevation view being a mirror of the front elevation view;

FIG. 2 is a right side elevation view thereof, with the left side elevation view being a mirror image of the right side elevation view;

FIG. 3 is a top plan view thereof; and,

FIG. 4 is a bottom plan view thereof.

1 Claim, 4 Drawing Sheets

FIG. 1

FIG. 2

FIG. 3

FIG. 4
